APPARATUS FOR DRYING VEGETABLE FIBER SUCH AS BAGASSE AND THE LIKE

Gaston J. Lipscomb, Montclair, N. J.

Application October 20, 1934, Serial No. 749,258

1 Claim. (Cl. 34—23)

The present invention relates to the apparatus for drying vegetable fiber such as bagasse, and aims generally to improve existing methods and apparatus for that purpose.

More particularly, the present invention aims to improve the method and apparatus for drying vegetable fiber as is disclosed in my copending application Serial No. 738,112, filed August 2, 1934, by providing a new method and apparatus which will substantially dry bagasse to a dryness of approximately 7% in a minimum of time and under materially reduced fire hazards.

One of the principal aims and objects of the invention is to provide an improved method and apparatus for drying bagasse which will give good efficiency, highly satisfactory drying as well as reduce the fire risk to a minimum.

The salient features of the method and the construction of the apparatus are best illustrated by reference to the accompanying drawing illustrating in diagram a suitable apparatus for carrying out the method.

In the drawing—

Fig. 1 is a section elevation of my improved apparatus for carrying out the method; and

Fig. 2 is an enlarged detail view of the feeding and regulating means of the drier.

As in the case of my prior application Serial No. 738,112, above referred to, the wet bagasse containing from 45% to 50% of moisture, is delivered to a drier casing through which hot air is circulated, the bagasse being fed to successive tiers during its progress through the drier casing.

According to the present invention, the wet bagasse is delivered to a feeding box, 10, which may be a circular sheet mounted above the drier casing 13. Rotatably mounted with the feeding box 10 is a vertical shaft 14 carrying a feeding cone 15 upon which the bagasse is delivered from a plurality of feed spouts 16 on either side of the feed cone so as to more uniformly distribute the bagasse upon the rotating feed cone. The feed cone may carry a plurality of radially disposed rabble arms 17 for spreading the bagasse into the openings of a stationary distributing plate 18. Mounted immediately below and closely adjacent to the plate 18 is an adjustable plate 19 having openings corresponding to the openings in the distributing plate, the plate 19 being adjustable around the shaft 14 so that it may be adjusted with reference to the plate 18 and thus vary the size of the openings in the distributing plate 18 to variably control the feeding of bagasse into the drier.

Below the distributing plate 18 is a plurality of

drying tiers 20 similar to those of my copending application, each tier comprising alternate reticulated sections 21 and open spaces 22, the reticulated sections of each tier being immediately below an open space in the tier above it so that as the bagasse is brushed off the section 21 of one tier by a rotating rabble arm 23, it will be brushed into an adjacent opening 22 and fall directly upon a reticulated support 22 below. The number and size of the tiers, as well as the number of rabble arms for each tier will, of course, vary according to the capacity of the plant and the degree of dryness to be desired.

According to the present invention, the drying is effected by moving the wet bagasse for a substantial distance in a current of very hot air or flue gas, preferably at a temperature of about 800° to 1000° F. to extract a substantial amount of moisture from the material and then completing the drying of the bagasse by moving it in a counter-current of hot air at a temperature of between 250° and 400° F.

The hot flue gases and heated air may be supplied from a suitable source, as for example, a Dutch oven 25 having a cook's furnace 26 adapted to burn a quantity of bagasse which advantageously may be a percentage of the bagasse dried in the drier. The cook's furnace of the oven 25 may be supplied with a forced draft in the usual manner and a secondary combustion chamber 27 as is usual. The products of combustion of the furnace are advantageously divided and may be variably controlled as by damper 27a, a major portion of the gas being passed through flue 28 to an annular air inlet 29 surrounding the feed box 10 and directed inwardly to the interior of the feed box, by means of radial openings or nozzles 30 so that the application of the hot flue gases to the wet bagasse will be as uniform as possible circumferentially of the drier.

The balance of the products of combustion from the Dutch oven are passed through a heat exchanger 31 which may advantageously be of any suitable design by means of which air, circulated by fan 32 may be heated to a suitable degree, the flow of flue gases through the heat exchanger 31, and hence the temperature of air heated thereby, being controlled by valve 33. The air heated by the heat exchanger 31 passes through conduit 34 to an annular hot air inlet 35 surrounding the drier casing 13 at its lower end, the hot air being admitted to the interior of the casing 13 by means of radial openings or nozzles 36 so that the application of heated air to the bagasse will be uniform circumferentially.

of the drier. Obviously the temperature of the hot flue gases entering the feed box 10 may be variably controlled by suitable means, as for example, a damper regulating the admission of air 5 to the secondary combustion chamber 27 of the oven 26.

A fan 38 is preferably provided to draw off the dust and moisture laden air and gases from the drier casing and preferably this fan is connected to the casing intermediate the flue gas inlet at the upper end of the drier and the hot air inlet 35 and the lower end of the drier. Preferably the exhaust fan 38 is connected to the drier by means of an annular outlet or exhaust 10 chamber 39, and the fan advantageously delivers the dust laden air and gases to a suitable dust collector which may be of the cyclone type. The fan 38 is of sufficient capacity as to produce a negative pressure with the casing 13. 15

It is important that the drying take place within an enclosed chamber and in the absence of air, except the hot air and gases which are circulated through the drier, and hence it is advantageous to provide an air lock both at the feeding and discharge end of the drier. This may be satisfactorily accomplished by means of the star wheel mechanism disclosed in my copending application, but in connection with the discharge I find the more satisfactory air lock is obtained according to the present invention. 20

Accordingly, the lower end of the casing 13 may comprise downwardly and inwardly inclined walls forming a discharge cone 41, the cone terminating at its lower end in a horizontal tube 42. The lower end of the shaft may be provided with a stirrer or scraper 43 to prevent bridging of the dried bagasse in the cone, and to permit a normal flow of dried material to the tube 42. A plunger 44 reciprocated by any suitable means, 25 as for example, a crank 45 and connecting rod 46 is mounted within the tube to discharge the bagasse from the discharge cone 41, the number of strokes of the plunger 44 as well as the diameter of the tube 42 being proportioned and designed so as to progressively discharge bagasse 30 in accordance with the capacity of the drier and the rate of feeding material to the feed box 10.

In order to provide an air lock against the admission of atmospheric air into the drier at the discharge cone, the tube 42 preferably terminates in reduced discharge tube 47 effective to retard the flow of dried bagasse except under pressure from the plunger 43. The cooperating action of the plunger 43 and the reduced discharge tube effect a compacting of the bagasse 45 fibers in the discharge tube effective to seal the tube 45 against the entrance of air and also to deliver the dried bagasse in partially compressed batches, which are more advantageously baled in 50 baling presses than when the material is loose and flocculent.

The shaft 14 advantageously extends longitudinally of the full height of the drier and may be advantageously driven by suitable speed reduction gearing 48 at the upper end. 5

Advantages of my present invention over the method and apparatus disclosed in my copending application Serial No. 738,112 are that a more complete drying of the bagasse may be effected in a shorter time and hence the capacity of the drier may be increased without serious liability to fires occurring in the drier. By first subjecting the wet bagasse to the hot flue gases which may be as hot as 800° to 1000° F. to partially dry them, and then finally drying the bagasse in a current of air at from 250° to 400° F., I am able to dry bagasse to a high degree of dryness (with a moisture content as low as 7%) in a relatively shorter time than was possible with the method disclosed in my copending application. For example, the drying may be completed according to the present invention, in 15 minutes, and preferably the exhaust or discharge outlet 39 is so located that bagasse is subjected to the hot flue gases for 60% of the drying time, and to the counter flow of hot air for approximately 40% of the drying time. This I find is an extremely efficient drying method and enables me to reduce the number of drying tiers over my prior method. 15

I claim: 20

Apparatus for drying loose vegetable fibers such as bagasse, comprising a closed vertical casing, a vertical shaft rotatably mounted in said casing, a conical distributor connected to the upper end of the shaft, means for introducing fibers into the casing and upon said distributor, a plurality of reticulated tiers spaced throughout the length of the casing, means for progressively conveying the fiber material from one tier to the next lower tier, an auxiliary furnace, means for conveying hot flue gases of approximately 750° F. from said furnace and introducing them into the top of said chamber in contact with the fibrous material, a heat exchanger heated by said furnace, means for circulating drying air through said heat exchanger and introducing it at approximately 250°-400° F. into the opposite end of said chamber, and means for withdrawing said hot flue gases and said cooler drying air from said chamber at a point between their points of introduction, the arrangement 35 permitting a current of hot flue gases moving in the direction of travel of the fibrous material during the first operation of drying period, and a current of cooler drying air moving in a counter direction to the movement of the fibrous material during the latter portion of the drying 40 period. 45
